UNITED STATES PATENT OFFICE.

GEORGE E. STEVENS, OF LYNN, MASSACHUSETTS, ASSIGNOR TO GENERAL ELECTRIC COMPANY, A CORPORATION OF NEW YORK.

SUCTION APPARATUS.

1,198,968.

Specification of Letters Patent. Patented Sept. 19, 1916.

Application filed November 20, 1913. Serial No. 802,072.

To all whom it may concern:

Be it known that I, GEORGE E. STEVENS, a citizen of the United States, residing at Lynn, in the county of Essex, State of Massachusetts, have invented certain new and useful Improvements in Suction Apparatus, of which the following is a specification.

My invention relates to suction apparatus for removing dust, lint, and dirt generally from floors, walls, ceilings, carpets, furniture, clothing, and articles and fabrics of all kinds, and the like, and it comprises various novel features of operation and construction and various novel combinations and arrangements of parts.

Among the advantages obtainable in connection with my invention I may mention that the apparatus can be made light, compact, strong, durable, convenient, and of good appearance; that it can be made simple, effective, and economical in operation; and that it can be manufactured easily and cheaply.

I have hereinafter illustrated and described in detail a suction or vacuum apparatus which is the best embodiment of my invention at present known to me; but while the invention extends to this particular form of apparatus and to its specific features and details, yet it is not confined thereto.

Various advantages of the apparatus shown besides those above mentioned will be apparent from my description, and the scope of the invention will be indicated in my claims.

In the accompanying drawings, Figure 1 is a vertical section through an apparatus constructed in accordance with my invention; Fig. 2 is a plan view of the apparatus, various parts being removed or broken away; Fig. 3 is a fragmentary sectional view illustrating a structural detail; Fig. 4 is a fragmentary sectional view at a surface corresponding to the line 4—4 in Fig. 2.

As will be seen from Figs. 1 and 2, the apparatus comprises a casing 1 of a generally cylindrical form having air inlet means 2 which may be connected with any desired form of dirt collecting or nozzle device (not shown) and air outlet means 3 which may be connected with any desired point of discharge, or may open directly into the atmosphere. Suction creating means com-

prising an exhauster 4 within the casing 1 causes a flow of air from the dirt collecting device through the casing and so produces a suction at said device, and the dust, dirt, or other material collected is removed from the air by separator means 5, which in the apparatus shown is also located within the casing 1. In this apparatus the suction creating means comprises a motor 6 for driving the exhauster 4,—this arrangement being preferable to a connection with an outside source of power,—and for the sake of compactness and for various other reasons the motor 6 is located within the casing 1 along with the exhauster 4 and the separator 5.

As shown, the exhauster 4 is arranged at the upper end of the casing 1 with the motor 6 beneath it. The exhauster comprises a rotary impeller 7 which revolves about an upright axis formed by an extension of the motor shaft 8, and also an inclosing structure 9 having in it various passages for the air and also a bearing 10 for said shaft 8. The impeller 7 is of the centrifugal type and receives the air acted on by it at its upper side. The motor 6 is arranged centrally in the casing 1 in the path of the air so as to be completely surrounded and cooled by it; and as the air enters the casing 1 from the inlet means 2 below the motor 6 it comes in contact with the motor before it has been heated by compression in the exhauster 4, which makes the cooling more effective than it would otherwise be. The motor field or body 11 (which may, if desired, be of the laminated type) is hung from the structure 9 by a number of screws, and a base part 12 is in like manner secured beneath the body 11. This base 12 serves to inclose the armature, the field coils, and other parts of the motor 6, and protect them from any dust or dirt that might otherwise find its way to them, and it also carries another shaft bearing 13 similar to the bearing 10 and a vertically adjustable step bearing 14 threaded through a suitable hole and held fast by a lock-nut 15.

On the lower side of the base 12 are legs 16 for supporting the motor and the exhauster and the parts associated with them when the apparatus is opened up as herein-after described. If greater ventilation of the motor is desired and entrance of small

amounts of fine dust to it is not deemed objectionable, the casing of the motor may be pierced to allow passage of the upwardly flowing air among the field coils and around the armature.

5 The separator 5 is arranged across the casing 1 so as to extend beneath the motor 6 in the path of the air, thus preventing the dirt, dust, and other material brought in 10 by the air from reaching the motor.

As shown the separator comprises a baggy strainer which, under the action of the air, bulges up around the motor, affording ample straining surface even with a fine fabric, 15 and also ample space for the air to come to rest and permit all heavier material to drop to the bottom of the casing 1. In the casing wall just above the inlet 2 is a shallow groove 17 to receive the expanding spring 20 wire ring 18 sewn into the hem of the separator bag 5. The ends of the wire 18, Fig. 3, fit into a short metal sleeve 19, one of them being preferably fastened so that there is no risk of the wire piercing the fabric.

25 It will be seen from Figs. 1 and 2 that the impeller 7 comprises a hub portion 20 at the center of a disk portion 21 that carries on its upper side a number of alternately long and short radial vanes 22 and 23, and 30 that it is inclosed in a central chamber in the structure 9,—a cover plate 24 secured in place by screws being removable to afford an opening for its introduction or withdrawal. The air ascending around the 35 motor 6 passes on up through three ducts or passages 25 that pierce the structure 9 outside of the impeller chamber to an upper chamber 26 between the upper side of said structure 9 and a cover 27 whose edge is 40 fastened tight against a gasket at the bottom of an annular groove 28, screws being employed for this purpose. From the upper chamber 26 the air descends into the impeller chamber through a central opening 45 29 in the cover plate 24, entering the passages between the upwardly extending and forwardly inclined inner ends 29^a of the guide vanes of the long impeller vanes 22 as it passes through the opening 29. The 50 purpose of the vanes 29^a is to direct and guide the incoming air on to the impeller vanes without shock, thereby improving the efficiency of the apparatus. The upper end of the shaft 8 is supported in a suitable 55 bearing, comprising in the present instance a jewel 30 mounted in the lower ends of a vertically adjustable screw member 31 and engaging a stud 32 at the bottom of a recess in the upper end of the shaft 8. As will be 60 seen from Figs. 1 and 2, the member 31 is secured in the middle of a beam 33 which extends across the opening 29 and has lateral feet at its ends that are secured to the structure 9 by two of the screws that hold the cover 65 plate 24 in place. The air leaves the counter-

clockwise revolving impeller 7 in tangential counter-clockwise streams and flows outward through gradually expanding more or less nearly involute-shaped passages 35 between the partition walls 36. At the outer ends 70 of these passages 35 the air passes down between the passages 25 through the openings 37 in the bottom wall or floor 38 of these passages (which is in effect an outward extension of the bottom wall of the impeller chamber) into an annular discharge passage 39 which lies between the central flange 40 of the structure 9 to which the motor body 11 is secured and the circumferential wall 41 of said structure 9, but is partially restricted 75 at various points by the walls of the passages 25 (Figs. 1, 2, and 4). From the annular passage 39 the air passes directly into the outlet 3. Preferably the passages and openings 35, 37, and 39 are so designed that 80 on the whole the outflow channel afforded by them gradually increases in cross section for all or a part of its length, so that the pressure of the air shall not be unnecessarily much above atmospheric when it reaches the 85 outlet 3. It will be seen that with the arrangement of the various passages and chambers in the structure 9 herein shown and described the space required by the ex-90 hauster is reduced to a minimum and satisfactory operation at the same time insured.

To allow the apparatus to be easily opened for removal of dirt from beneath the separator 5, the structure 9 and its cover 27 may be made as a sort of removable top or lid 43 for the lower portion 44 of the casing 1. As shown in Figs. 1 and 2, the lower part of the casing has a smooth rounded upper edge 45, and the structure 9 has at its lower outer edge a flange 46 with an annular groove 47 adapted to fit over the edge 45, there being a rubber or other suitable gasket 48 at the bottom of the groove 47 to make a tight joint. For fastening the structure 9 and associated parts on the main casing part 100 44 are employed three fasteners 50 equally spaced around the upper edge of the part 44. Each of these fasteners 50 consists of a lug 51, a link 52 having one end pivoted thereto, and a part 53 pivoted in a fork at the 105 other end of said link 52. This part 53 has at one end a thumb piece 54 and at the other a foot 55 adapted to engage behind an annular shoulder 56 at the upper edge of the flange 46. The arrangement of the pivots, 110 etc., is such that when the thumb piece 54 is pressed toward the structure 9 a certain distance a dead center is passed at which the compression of the gasket 48 is a maximum, and the expansion of the gasket thereafter 115 causes it to move the rest of the way to the position shown. For convenience in lifting the lid 43 a handle 57 is secured to the cover 27. Electrical connection may be made by various well-known forms of attachment de-120 125 130

vice with two suitably insulated contact pins 58 mounted on the structure 9 and connected by wires (not shown) with the motor 6.

From the foregoing description it will be seen that the device comprises a small number of rugged and comparatively simple parts that can be cheaply manufactured and cheaply and expeditiously assembled. Thus the main casing part 44 and the cover 10 27 can be easily made from sheet aluminum; the parts 2, 7, 9, 12, 24, 33, and 57 may be ordinary aluminum castings or forgings, and the motor can be one of well-known type; and all the parts require but a small 15 amount of relatively simple machine work or polishing, etc.

What I claim as new and desire to secure by Letters Patent of the United States is:—

1. In a suction apparatus, the combination of a casing having an air inlet at the bottom, a structure mounted on the casing which forms a closure therefor, said structure being provided with an impeller chamber, partitions that form discharge passages, 25 a chamber receiving air from the passages, a centrally located motor supporting flange, and an outlet from the chamber, an impeller located in the impeller chamber and wholly above the motor, a vertical shaft motor for 30 driving the impeller which is secured to the under side of said flange so that air from the inlet flows over the motor and cools it on its passage to the impeller, and a passage which conveys air from the casing inlet 35 through said structure to the inlet ends of the vanes of the impeller.

2. In a suction apparatus, the combination of a casing having an air inlet at the bottom, a structure mounted on the casing 40 which forms a closure therefor, said structure having an impeller chamber which has a central opening on its upper side, partitions that surround the impeller and form gradually expanding passages, an outlet 45 that communicates with the passages, and ducts that convey air from the under to the upper side of said structure, a cover which with the structure forms a chamber receiving air from the ducts and supplying it to 50 said central opening and the impeller, an impeller located in said chamber, a vertical shaft motor for driving the impeller, said motor being cooled by the air on its passage from the inlet to said ducts.

3. An exhauster comprising a structure having in it a central impeller chamber with axial inlet means, a receiving and delivery passage surrounding said impeller chamber and in communication therewith, and passages from one side thereof to the other around said impeller chamber; and a rotary impeller in said impeller chamber receiving air axially through the aforesaid inlet means.

4. An exhauster comprising a structure

having in it a central impeller chamber with axial inlet means, a receiving and delivery passage surrounding and communicating with said impeller chamber and having diverging tangential extensions, an annular discharge passage beside said receiving passage communicating with the aforesaid extensions thereof, and passages from one side of said structure to the other around said receiving and delivery passage; and a 70 rotary impeller in said impeller chamber receiving air axially through the aforesaid inlet means.

5. An exhauster for a suction apparatus comprising a structure adapted to form the 80 removable cover of a casing inclosing the apparatus and having in it a central impeller chamber with an inlet opening from above, a receiving and delivery passage surrounding said impeller chamber and in communication therewith, and passages from 85 its lower to its upper side around said impeller chamber; a rotary impeller in said impeller chamber arranged to revolve about an upright axis and receive air at its upper 90 side through the aforesaid inlet; and a motor for driving said impeller mounted on said structure.

6. In an apparatus of the character described, the combination of a casing, a 95 structure removably supported thereon which forms a cover and contains an impeller chamber, a discharge chamber, partitions forming gradually diverging 100 passages between the impeller and discharge chambers, and an outlet leading from the discharge chamber, an impeller in the impeller chamber, a vertical shaft motor within the casing which is attached to and supported by said structure on its under side 105 for rotating the impeller, means for attaching said structure to the casing, an inlet from which air entering the casing passes over the motor and cools it before entering the impeller, a passage conveying air from 110 the under to the upper side of said structure, and a cover for said structure which cooperates with it to form a chamber that receives air from said passage and supplies it to the inlet ends of the impeller vanes. 115

7. In an apparatus of the character described, the combination of a casing, a structure mounted thereon which forms a cover and contains an impeller chamber, a discharge chamber, partitions forming 120 gradually diverging passages between the impeller and the discharge chambers, and an outlet leading from the discharge chamber, an impeller in the first named chamber having main and guide vanes, a plate 125 that covers the impeller and has an opening into which the guide vanes project and through which air enters the impeller, a vertical shaft motor which is attached to the under side of said structure, a bearing for 130

the lower end of the motor shaft carried by the frame of the motor, a member which supports the bearing for the upper end of the motor shaft, and means arranged to admit air to the casing in such manner that it passes over the motor and cools it before entering the impeller.

8. In an apparatus of the character described, the combination of a casing, a structure mounted thereon which forms a cover and contains an impeller chamber, a discharge chamber, partitions forming gradually diverging passages between the impeller and the discharge chambers, and an outlet leading from the discharge chamber, an impeller located in the impeller chamber having main radial vanes and also axially extending guide vanes that direct the incoming air to the main vanes, a motor supported by said structure which drives the impeller, a cover which is fastened to said structure and with it forms an inlet chamber for the impeller, an inlet in the casing, and ducts in said structure located between the impeller chamber and the periphery of the structure which receive air from the under side of said structure and deliver it to said inlet chamber.

20 9. In an apparatus of the character described, the combination of a casing, a structure mounted thereon which forms a cover and contains an impeller chamber, a discharge chamber, partitions forming

gradually diverging passages between the impeller and the discharge chambers, and an outlet leading from the discharge chamber, an impeller located in the impeller chamber having main radial vanes and also axially extending guide vanes that direct the incoming air to the main vanes, a plate located on one side of the impeller which forms one side of its chamber and has a central opening whose wall surrounds the periphery of the guide vanes and assists in guiding the air, a motor supported by said structure which drives the impeller, a cover which is fastened to said structure and with it forms an inlet chamber for the impeller, an inlet in the casing, and ducts in said structure located between the impeller chamber and the periphery of the structure which receive air from the under side of said structure and deliver it to said inlet chamber.

50 In witness whereof, I have hereunto set my hand this seventeenth day of November, 1913.

GEORGE E. STEVENS.
